UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

MULTIUNIT TANK CAR

Application filed June 11, 1931. Serial No. 543,590.

This invention relates to tank cars and more particularly multiple unit tank cars, especially of the type wherein the tanks are mounted longitudinally and are adapted to be individually removed or replaced without disturbing other tanks in case it is desired to distribute the tanks to customers.

One object of the invention is to provide an improved multiple unit tank car wherein a number of tanks may be supported independently of each other and yet be disposed within the permissible side limits of a car and still have the center of gravity of the car maintained at a relatively low point so that in all substantial respects the balance of the car will be comparable to the single unit tank cars.

A further and more specific object of the invention is to dispose a pair of lower tanks, one at each side of the car, and another tank or pair of tanks above and between the lower tanks, all of which are sufficiently supported independently of each other so that one tank does not rest upon or be supported by another tank, although in certain specific modifications supporting contact between tanks may be effected to a limited extent while still utilizing the improved tank supporting means of this invention. In this way maximum tank capacity is obtained for a multiple unit car without endangering the car with a high center of gravity or unstable anchoring or fastening of the tanks.

Another object of the invention is to provide an improved underframe which is adapted to effectively cradle and anchor the tanks in position.

A further object is to provide an improved arrangement for anchoring the tank bands and to support in a simplified manner a running board in a convenient and safe location.

This invention also contemplates the provision of a multi-unit tank car comprising an underframe adapted to directly support a plurality of longitudinally arranged tanks, said underframe supporting a superstructure adapted to support a plurality of longitudinally arranged tanks at an elevation above the supporting portions for the first-named tanks.

This invention also contemplates the provision of a railway car adapted to support a plurality of longitudinally extending tanks; said car including an underframe, and a superstructure secured thereto and including a framework adapted to support a row of tanks longitudinally of the underframe on each side of the central longitudinal axis of the car.

Other objects and advantages will be more apparent to those skilled in the art from the following description of the accompanying drawings wherein,

Fig. 1 is a fragmentary side elevation of a multiple unit tank car embodying the invention, parts of which are broken away to show details of construction.

Fig. 2 is a plan view of Fig. 1, parts of which are also broken away to show details of construction.

Fig. 3 is an enlarged transverse vertical section taken on the line 3—3 of Fig. 2.

Fig. 4 is a fragmentary side elevation looking at Fig. 3 from the left with the lower outer tank removed, parts also being broken away to show other parts.

Fig. 5 is a plan view of one corner portion of the underframe with the tanks removed, this view showing only that portion of the underframe to one side of the center sill.

Fig. 6 is a plan view of a casting for anchoring the tanks looked at in the direction of the arrow 6 in Fig. 3.

Fig. 7 is a vertical transverse section through an underframe having a floor.

In the drawings which illustrate the invention there is provided, as shown in Figs. 3 and 7, center sills 2—2, side sills 3, bolster diaphragms 4—4 which with the top and bottom bolster cover plates 5 and 6 form a conventional car underframe. In the modification shown in Fig. 7, the element F which serves as a top bolster cover plate is intended to withstand the usual stresses imposed upon such element of a bolster and extends entirely across the car and substantially from end sill to end sill forming a floor for the car and developing in this instance a conventional flat car. Extending transversely of the underframe from side sill to side sill at each end of

the car are angles 6', to the vertical legs of which are attached vertically extending posts 7, which extend upwardly above the under-frame sufficiently high to support a running board 8 as best shown in Fig. 3. Intermediate 5 the bolsters are cross bearers 9—9, which like the bolsters, are formed with diaphragms 4, illustrated in Fig. 7, which diaphragms in the cross bearers are single, that is, each cross bearer is formed from a single plate at each 10 side of the center sills, whereas in the bolsters the diaphragms comprise parallel spaced conventional pressed plates riveted to the center sills, side sills and top and bottom cover plates.

Connected to the cross bearers by gussets 26a and rising from said cross bearers are Z-shaped posts 12, which like the posts 7 extend upwardly far enough to contribute to 20 the support of the running board 8 in the same manner as posts 7. Upon the under-frame or flat car thus provided a supporting framework is employed to carry a plurality of tanks in such manner that the load imposed 25 by such tanks and other lading shall be transmitted to the center sills. In addition to this the tanks just referred to are positioned at a level considerably above the underframe so that tanks at a lower level may be carried 30 near the outer side edges of the car, but in such manner that a large percentage of the load imposed by said outer tanks and their lading shall be transmitted through the bolsters and cross bearers directly to the center 35 sill which with its top cover plate 13 extends from end to end of the car structure. To support the tanks in the upper level a superstructure is built onto the underframe, said superstructure comprising a framework 40 which includes plate girders connected to the upper sides of the bolsters and cross bearers with stiffening means hereinafter specifically described for reinforcing said plate girders. For convenience, the framework comprising 45 the plate girders and associated parts is hereinafter referred to as the upper tank supporting means, while the cross bearers and body bolsters comprise in effect the lower tank supporting means, the whole, however, being connected to and forming a part of the under-frame so that in one aspect of the invention the underframe is provided with offset tank supporting portions, one offset portion being at the level of the cross bearers and the other 50 at the higher level of the upwardly extending framework including the plate girders and their immediately associated parts. Specific means by which actual supporting contact is made for the outer lower set of longitudinal tanks and the upper inner set of longitudinal tanks is shown to advantage in 55 Fig. 3.

The superstructure which is more specifically described hereinafter provides for supporting a plurality of tanks on each side of

the central longitudinal axis of the car and in longitudinal planes within or inside of vertical planes defined by the central longitudinal axes of the lower tanks, all of which will be apparent from the description to follow. 70

Referring now to Fig. 3 it will be noted that the superstructure comprises a framework including plate girders arranged on each side of the central longitudinal axis of the car and formed of plates 48 (see Fig. 2) which extend between the angles 6 at each end of the car. These plates 48 constitute the web portions of the plate girders and their lower edges are secured to the bottom chords 37, 80 angles in the instance shown, riveted or otherwise secured to the car underframe as clearly shown in Fig. 3. The upper edges of the plates 48 are outwardly flanged as at 48' and constitute the top chords of the plate 85 girders, and to these top chords or flanges 48' channels 46 are riveted or otherwise fastened, the channels in the instance shown, being inverted and facing diagonally inward toward the center sills 2. Secured to the inner flanges of the channels 46 are a plurality of connector plates 47 which rest upon and are secured to the horizontal flanges of angles 16, secured to the webs of posts 12 by fasteners 20 and having portions thereof downwardly 90 bent as at 16' to lie against the inner surfaces of the plates 48 and to be fastened thereto in any suitable manner as by rivets. The lower ends of portions 16' of the angles 16 are connected by rivets 49a to gussets 26 and the latter are securely fastened as by rivets to the car underframe as shown in Fig. 3. The portions 16' of the angles 16 are also connected to the bottom chords 37 of the plate girder 95 by suitable fasteners such as the rivets 49. 100

The superstructure also includes inner tank supporting members 21 comprising Z-sections arranged on each side of the posts 12. These members 21 are of substantially the same length as the plate portions 48 and are secured to and supported by brackets 18 connected to the posts 12. In practice it has been found desirable to arrange the brackets 18 adjacent the angles 16 and to connect the brackets and angles together by suitable fasteners such as the rivets 20 which serve not only as a connecting means for the brackets and angles but also as fasteners for connecting the said angles and brackets to posts 12. 110

In Fig. 3 the upper tanks are designated at 40 and the Z-sections 21 constitute inner supports for these tanks; the latter being arranged on each side of the central longitudinal axis of the car and being also supported by cradles 43, the latter serving also as anchor castings to prevent longitudinal shifting of the tanks. Intermediate the ends of the car the cradles 43 are formed to provide upper and lower pairs of curved 115 seats 44 (see Fig. 6) adapted to receive the 120

adjacent end portions of upper tanks 40 and lower tanks 39, respectively. Obviously at the ends of the car these double cradles are not required and hence the end cradles comprise single upper and lower seats 44 (see Fig. 5). The cradles 43 are secured to the channels 46 and are preferably arranged adjacent the angles 16 so that the direct load imposed on the cradles by the tanks may be directly carried by reinforced portions of the plate girders. For further stiffening the car underframe and particularly for furnishing additional connections between the superstructure and the underframe the plate girders are connected to the cross bearers 9 by means of gussets 38 as shown clearly in Fig. 2.

Secured to the underframe adjacent the bottom chords 37 of the plate girders forming a part of the superstructure are cradle members 50 which extend longitudinally of the car and which are riveted as shown at 51 to the underframe. The lower tanks 39 are supported by these cradle members 50 and by cradle members 52 riveted as at 53 to the side sills 3. It is to be noted that the lower tanks 39 while being supported by the cradle members 50 and 52 have their ends arranged in the curved seats 44 of the cradle members 43 and the tanks 39 are thus restrained against longitudinal shifting. Pivotally connected as at 52' to the cradle members 52 are tank bands 58 the upper ends of which are flanged to provide ears 58' which receive eye bolts 60, the free ends of which latter are adapted to engage the hooked ends 61' of curved rods 61 anchored by bolted connections 62' in the channels 46. The eye bolts 60 are provided with adjusting nuts for an obvious purpose.

For securing the upper tanks 40 against vertical shifting and to retain them in their seats 21 and 43, tank bands 62 are provided which are connected to band anchors 63 riveted to an inverted channel 66 which extends from end to end of the car between the end posts 7 and is supported by and connected to said posts 7 and posts 12 by gussets 64 riveted to the posts and channel 66 as shown at 65. The free ends of the bands 62 are upwardly flanged as at 65' to receive eye bolts 60 having curved ends which engage the hooked ends 69' of curved rods 69, similar to the rods 61 and connected to the channels 46 by bolted connections similar to those indicated at 62'. The eye bolts 60 which connect the bands 62 and rods 69 are also provided with adjusting nuts for an obvious purpose.

This car provides a running board 8 which is preferably arranged substantially parallel to the longitudinal center line of the underframe and which extends between the end ladders E and which comprises, in the instance shown, a plurality of longitudinally extending planks H supported by Z-shaped

brackets G secured to the channel 66. As clearly shown in Fig. 1, a hand rail 70 is provided which extends between the end ladders E and is supported intermediate its ends by posts 72 secured to the running board 8.

From the above description it is believed that the construction of the car of the present invention will be fully apparent to those skilled in the art. It is to be noted that a plurality of tanks are supported by the underframe on each side of the longitudinal center line of the underframe, the tanks being arranged end to end in rows, one row being arranged adjacent the side sill 3 while the other row is supported at an elevation above the first-mentioned row. The individual tanks in each row are individually supported and adjacent ends of adjacent tanks are spaced from each other and intermediate adjacent tanks the castings 44 serve to prevent longitudinal shifting of the tanks. It is also obvious that any desired tank may be removed from the underframe independently of and without disturbing any other tank. It is believed that in a car of the type shown and described herein the load is symmetrically arranged and distributed. The car of the present invention also provides the necessary safety devices such as hand rails and running board.

The drawings herein illustrate one embodiment of the invention but it is to be understood they are for illustrative purposes only and various changes in the form and proportions of the construction may be made within the scope of the appended claims without departing from the spirit of the invention.

What is claimed is:

1. A multiple unit tank car having a plurality of lower tanks, an upper tank, means for supporting said upper tank above and between said lower tanks, and means whereby each tank is longitudinally anchored independently of the other.

2. A multiple unit tank car comprising a pair of lower tanks disposed with their longitudinal axes lengthwise of the car and transversely spaced from each other, an upper tank having its longitudinal axis also disposed lengthwise of the car, and means for supporting said upper tank above and between said lower tanks and independently thereof.

3. A multiple unit tank car comprising a pair of lower tanks disposed with their longitudinal axes lengthwise of the car and transversely spaced from each other, an upper tank having its longitudinal axis also disposed lengthwise of the car, means for supporting said upper tank above and between said lower tanks, and means for individually holding said tanks whereby they may be separately removed or replaced independently of the remaining tanks.

4. A multiple unit tank car comprising an

- underframe having means providing offset tank supporting levels, a pair of transversely spaced tanks supported by said underframe at one of said levels, tanks supported by said underframe at another of said levels and arranged respectively on each side of the longitudinal center line of the underframe, posts projecting upwardly from said underframe, and a running board supported by said posts.
5. A multiple unit tank car comprising an underframe having means providing offset tank supporting levels, a pair of transversely spaced tanks carried at the outside of said car at one of said levels, a plurality of tanks disposed inwardly of and above said outer tanks and carried at the other level, posts projecting upwardly from said underframe between said upper tanks, and a running board carried by said posts.
10. A multiple unit tank car comprising an underframe having means providing offset tank supporting levels, a pair of transversely spaced tanks carried at the outside of said car and at one of said levels, a plurality of tanks disposed inwardly and above said outer tanks and carried at the other level, posts projecting upwardly from said underframe between said upper tanks, bands for holding said upper tanks, and means associated with said posts for anchoring said bands.
15. A multiple unit tank car comprising a center sill and side sills, cross bearers between said sills, longitudinally extending cradles disposed at the outer ends of said cross bearers, tanks supported in said cradles lengthwise of said car, means supported by said cross bearers and center sill and projecting upwardly between said tanks, longitudinally extending cradles supported by said upwardly extending means adjacent the central portion thereof, other cradles also carried by said upwardly extending means, and tanks carried by the cradles of said upwardly extending means.
20. A multiple unit tank car comprising an underframe having longitudinally extending cradles carried near both sides of the underframe, tanks carried by said cradles, said underframe having means projecting upwardly between said tanks, longitudinally extending cradles carried by said latter means near the center thereof, tanks supported on said latter cradles, and anchor means carried by said upwardly extending means and disposed between and adapted to engage the end portion of the adjacent lower and upper tanks.
25. A multiple unit tank car, an underframe having a plurality of pairs of tank supporting elements arranged on each side of the longitudinal center line of the car for supporting a plurality of tanks on each side of the longitudinal center line of the car, certain of said pairs of tank supporting elements being arranged in a plane above the remainder of the elements.
30. In a multi-unit tank car, an underframe having a plurality of pairs of tank supporting elements arranged on each side of the longitudinal center line of the car for supporting a plurality of tanks on each side of the longitudinal center line of the car, certain of said pairs of tank supporting elements being arranged in a plane above the remainder of the elements, and independent clamping means for holding each of the tanks in position.
35. A multiple-tier multi-unit tank car comprising an underframe, cradle members for supporting a plurality of tanks on each side of the longitudinal center line of the car with their longer dimensions parallel to the longitudinal axis of the car, and other cradle members arranged at an elevation above the first-named cradle members and on each side of the longitudinal center line of the car for supporting a plurality of tanks between said first-mentioned tanks.
40. In a multi-unit tank car, an underframe, means on the underframe for supporting tanks on each side of the longitudinal center line of the underframe, and other supporting means carried by the underframe for supporting tanks on each side of the longitudinal center line of the underframe at an elevation above the first-named tanks.
45. A multiple-tier multi-unit tank car comprising an underframe having longitudinally arranged cradle members forming longitudinal seats for supporting tanks with their longer dimensions parallel to the longitudinal axis of the car, an upper series of tanks supported above and between the first-mentioned tanks and arranged on each side of the longitudinal center line of the car, and independent means for clamping each of the tanks to its supporting members.
50. A multiple-tier multi-unit tank car comprising an underframe having longitudinally arranged cradle members forming longitudinal seats for supporting tanks with their longer dimensions parallel to the longitudinal axis of the car, an upper series of tanks supported above and between the first-mentioned tanks and arranged on each side of the longitudinal center line of the car, and independent means for clamping each of the tanks to its supporting members, said supporting means for the tanks being so arranged that any desired tank may be removed from the underframe without disturbing any other tank.
55. In a multi-unit tank car, an underframe having a plurality of pairs of tank supporting elements arranged on each side of the longitudinal center line of the car for supporting a plurality of tanks on each side of the longitudinal center line of the car, certain of said pairs of tank supporting elements

underframe, and tank supporting elements on each side of the longitudinal center line of the car for supporting tanks between the first-named tanks and at a elevation above the latter whereby any tank may be removed from its support without disturbing any other tank.

16. In a multi-unit tank car, an underframe, longitudinally extending cradles supported by the underframe arranged in pairs and each pair adapted to support a plurality of tanks positioned end to end adjacent each side of the underframe, a tank supporting element on each side of and adjacent the longitudinal center line of the car, said supporting elements extending longitudinally of the car in a horizontal plane above said cradles and being adapted to support upper rows of tanks between the first-named tanks.

17. In a multi-unit tank car, an underframe, cradle members secured to the underframe for supporting tanks on each side of the longitudinal center line of the car with their long axes longitudinal to the car, and a tank supporting superstructure supported by the underframe between the said cradle members for supporting tanks between said first-named tanks at a higher elevation and on each side of the longitudinal center line of the car.

18. In a multi-unit tank car, an underframe, tank supporting members carried by the underframe, tanks retained in said members, said members being arranged to hold the tanks with their longer dimensions parallel to the longitudinal axis of the car and in sets, certain of said sets being arranged between and at an elevation above the remainder and all of said sets being arranged outside of the longitudinal center line of the car.

19. In a multi-unit tank car, an underframe, tank supporting members carried by the underframe, tanks retained in said members, said members being arranged to hold the tanks with their longer dimensions parallel to the longitudinal axis of the car and in sets, certain of said sets being arranged between and at an elevation above the remainder and all of said sets being arranged outside of the longitudinal center line of the car, and a running board arranged above the tanks and substantially in a plane parallel to the longitudinal center line of the car.

20. A multi-unit tank car comprising an underframe, seats supported by the underframe, tanks held in the seats, said seats being arranged to hold the tanks with their longer dimensions parallel with the longitudinal axis of the car and in sets, each of said sets being arranged outside of the longitudinal center line of the car and the ends of the tanks being spaced apart from each other, and fixed means supported by an underframe part above the lower-most parts

of the tanks for restraining the latter against longitudinal shifting.

21. In a multi-unit tank car, an underframe having a plurality of lower tanks supported thereon, and means supported by the underframe for holding a plurality of upper tanks above and between said lower tanks and independently of the latter whereby any tank may be removed from the underframe without disturbing any other tank.

22. In a multi-unit tank car, an underframe having a plurality of lower tanks supported thereon, a superstructure secured to the underframe and arranged between said lower tanks, means on the superstructure for holding a plurality of upper tanks above and between said lower tanks and outside of the longitudinal center line of the car, said holding means being adapted to support said upper tanks independently of the lower tanks whereby any tank may be removed from the underframe without disturbing any other tank.

In witness whereof I have hereunto set my hand.

VICTOR WILLOUGHBY.
